HEARING AID

David E. Young, Winter Park, Fla., assignor to Electone
Hearing Aid Company, a corporation of Florida

Filed Feb. 1, 1968, Ser. No. 10,412

Term of patent 14 years

U.S. Cl. D26—14
Int. Cl. D24—04

FIG. 1

FIG. 2

FIG. 3

FIG. 5

FIG. 4

FIG. 1 is a rear elevation view of a hearing aid illustrating my new design;

FIG. 2 is a side elevation view;

FIG. 3 is a top plan view;

FIG. 4 is a bottom plan view; and

FIG. 5 is a perspective view, on an enlarged scale.

I claim:

The ornamental design for a hearing aid, as shown.
